UNITED STATES PATENT OFFICE

131,791

DESIGN FOR A CLOTHES HANGER

Gilbert J. Rhodes, New York, N. Y.

Application January 7, 1942, Serial No. 105,053

Term of patent 14 years

To all whom it may concern:

Be it known that I, Gilbert J. Rhodes, a citizen of the United States of America, residing in New York city, county of New York, and State of New York, have invented a new, original, and ornamental Design for a Clothes Hanger, of which the following is a specification, reference being had to the accompanying drawing, forming part thereof.

Fig. 1 is a front elevational view of a clothes hanger, showing my new design.

Fig. 2 is a bottom edge elevational view thereof.

I claim:

The ornamental design for a clothes hanger, substantially as shown.

GILBERT J. RHODES.
